CLAIM

The ornamental design for a urine deflector, as shown and described.

DESCRIPTION

FIG. 1 is a perspective view of a urine deflector showing my new design;

FIG. 2 is a left side elevational view thereof, the opposite side being a mirror image;

FIG. 3 is a rear elevational view thereof;

FIG. 4 is a front elevational view thereof;

FIG. 5 is a bottom plan view thereof; and,

FIG. 6 is a top plan view thereof.

The dashed lines represent a toilet for use with the present design, and form no part of the claimed invention.
